(57) CLAIM

The ornamental design for a cuticle nipper, as shown and described.

DESCRIPTION

FIG. 1 is a front perspective view of an embodiment of a cuticle nipper according to the invention;

FIG. 2 is a left side view of the cuticle nipper according to the invention;

FIG. 3 is a right side view of the cuticle nipper according to the invention;

FIG. 4 is a top view of the cuticle nipper according to the invention;

FIG. 5 is a bottom view of the cuticle nipper according to the invention;

FIG. 6 is a front view of the cuticle nipper according to the invention; and,

FIG. 7 is a back view of the cuticle nipper according to the invention.
